UNITED STATES PATENT OFFICE.

GEORGE R. VOLLMAN, JR., OF CINCINNATI, OHIO.

GARMENT SUSPENDER.

Application filed May 10, 1927. Serial No. 190,291.

This invention relates to garment supports and is particularly directed to a suspender of the type supporting a garment from the shoulders of the person.

5 It is an object of this invention to provide a garment suspender, supported from the shoulders of the person, having a sliding attachment at the hip portions of the trousers and the front and rear straps for respective 10 suspender sides being continuous to accommodate for strains imparted to either the front or rear portions of the straps by utilizing the slack created on one side, as the back is bent, to be taken up, through the 15 sliding attachment, by the strained strap portion on the other side.

It is another object of this invention to provide clasp mountings for this type of suspender through which the elastic straps 20 may easily slide without damage to the straps, the clasps having roller characteristics and the straps throughout the range of sliding movement being provided with non-stretchable strips in engagement with the 25 clasps.

Still another object resides in the suspender attachment means wherein the elastic straps are reinforced and prevented from stretching at the point of sliding engagement 30 with the clasp and the elastic relieved of contact with the clasp preventing fraying and breaking of the elastic caused by the rubbing of the metal parts over the stretched elastic.

35 Other objects relate to the particular arrangement of the straps giving greater comfort to the user and preventing any undue strains upon the suspender structure, to greater ease in attaching the suspender when 40 worn beneath the shirt, and to features of adjustment and fabrication.

Further objects and advantages will be more fully set forth in the description of the accompanying drawings forming a part of 45 this specification, in which:

Figure 1 is a general perspective view illustrating the improved suspender mounted upon a person.

50 Figure 2 is a sectional view taken on line 2—2, Figure 1, detailing the structure at the juncture of the straps in the rear.

Figure 3 is a detailed plan view illustrating the non-elastic reinforcement strip at the point of the button engaging clasps.

Figure 4 is a detailed sectional view taken 55 on line 4—4, Figure 3, showing the mounting of a clasp.

Figure 5 is a side view of the suspender strap at the point of reinforcement showing the elastic in unstretched condition. 60

The attachment of the suspenders to the trousers for proper suspension is in this case at two points or at the hip portions of the trousers. This arrangement of the suspender permits freer movement of the body since 65 the hips may be termed the pivot points for direct forward and backward movement of the upper part of the body, and may thus be utilized to constitute the same means for the suspenders. Any flexing or twisting of 70 the back, stretching a front or rear strap in abnormal cases would impart a breaking strain upon the elastic or upon the attachment means. However, in this instance, the straps are free to adjust themselves, as these 75 strains are imparted to them, having a sliding connection at the points of attachment to the trousers.

The pair of straps, one at each side of the body are substantially continuous, and in the 80 form of loops extending from the point of juncture of the respective straps centrally of the back over the shoulders and downward to the point of suspension and then upward as rear portions to be attached to the previously 85 mentioned point of juncture.

The slack created in that portion of a respective strap, either front or rear on the side concaved by flexing of the back is taken 90 up by the strap under load, due to the continuity of the straps and the fact that the straps at the point of trouser suspension slidably pass through the clasps. The engagement is through a roller on the clasps and non-stretchable strips attached to the elastic 95 straps.

Referring to the drawing, the suspender is indicated generally as at 1, being shown in its entirety and in mounted position in Figure 1. The pair of straps 2—2, each constituting 100 a front and rear strap, are in the form of loops with suitable adjustment means provided for lengthening the strap loops. The formation of these loops is by stitching the respective ends of the straps between an elastic juncture strip 3 disposed longitudinally of the person's back when in mounted position. 105 This juncture strip is folded upon itself and

stitched along its margin securing in adjacent relation the corresponding ends of the respective straps.

Clasps 4 are disposed one upon each of the strap loops 2 intermediate thereof. Each clasp is formed of wire to provide a slot 5 at one end and a loop portion 6 at the other with an intermediate wide portion 6^a large enough to receive the button over which the clasp is inserted. The straps are extended through the slotted portions of the clasps and the loops depend therefrom as shown in Figure 1, to be engaged about buttons on the trousers.

The buttons are either on the inside or outside of the trousers, preferably the former. It is convenient to attach the suspender when worn beneath the shirt, since the hips are easily accessible from the open front of the shirt for attaching the clasps. The shirt is thereby held at the clasps since the shirt is between the same and the button and is held about the button.

The straps engage against wide rollers 7 mounted about the upper cross bars 7^a of the clasps. The clasp structure is reinforced at the lower end of the slot by a clasp 8 binding together the downwardly extending clasp forming wire lengths.

Due to their disposition on the person, the elastic straps are turned substantially upon themselves at the point where they engage the clasp rollers. This comparatively sharp creasing of the elastic, coupled with the suspended load overstretching the elastic at this point, tends to break or fray the straps. In order to suitably reinforce these straps at this point and to provide a hardened non-stretchable surface for the rollers they are engaged upon straight cut fabric strips 9 attached to

the straps. These strips are of sufficient length to provide a bearing for the clasps throughout the extent of strap shifting due to the movement of the person. The strips 9 are secured at their ends by stitching to the elastic strap.

Adjustment means are provided for the straps by making the same in two sections, 11, 12. A respective strap section 11 after extending through its clasp is passed through an elongated ring 10, lapped over as at 11^a and 50 stitched. The end of the second section 12 is also passed through the ring 10 but is provided upon its end 12^a with a clamp 13 of common construction utilized in suspenders. This clasp encircles that portion of the section over which the end is lapped and is designed to permit a sliding movement thereof on the encircled strap portion for adjusting the length of the strap and operative to impinge the material so as to be set in any desired 60 position.

Having described my invention, I claim:

A suspender of the class described, comprising, a pair of elastic straps in the form of loops having their ends fastened together joining the loops, each loop adapted to encircle a shoulder of the wearer, button clasps at the lower end of each loop adapted to be attached to the hip portions of the garment supported, a roller on each clasp for engagement with the strap, and a non-stretchable reinforcing strip attached to said strap loops at the point of clasp engagement as a bearing for the clasp roller throughout the range of its engagement.

In witness whereof, I hereunto subscribe my name.

GEORGE R. VOLLMAN, JR.
